UNITED STATES PATENT OFFICE.

FRANK L. DORSK, OF BALTIMORE, MARYLAND, ASSIGNOR TO MARYLAND TOY MANUFACTURING COMPANY, INC., A CORPORATION OF MARYLAND.

TOY.

1,342,945.

Specification of Letters Patent.

Patented June 8, 1920.

Application filed January 20, 1920. Serial No. 352,726.

To all whom it may concern:

Be it known that I, FRANK L. DORSK, a citizen of the United States, residing at Baltimore, in the State of Maryland, have 5 invented certain new and useful Improvements in Toys, of which the following is a specification.

This invention relates to improvements in toys, and has for its object to provide a simple, cheap and attractive toy for the amusement of children, and further to so construct said toy that the parts thereof can be folded to save space and to prevent breakage in shipment.

15 The invention consists of the novel construction and arrangement of the parts hereinafter more fully set forth in the following specification and pointed out in detail in the appended claims.

20 In the accompanying drawing:—

Figure 1 is a side elevation of my invention, showing one end of the base raised in the position it assumes as the toy is drawn along the ground.

25 Fig. 2 is an end view of Fig. 1.

Fig. 3 is an enlarged detail view showing one of the parallel bars folded down upon the base.

Referring to the accompanying drawings 30 forming part of this specification, and in which like reference numerals designate like parts throughout the several views thereof, 1 designates a base having sides 2 projecting from the under surface thereof in which the 35 wheels 3 are mounted. The said wheels 3 are mounted upon the axles 4 off their centers, as seen in Fig. 1, so that when the toy is drawn along the ground a rocking motion will be imparted to the base 1 and cause the 40 figures mounted thereon to swing and revolve. The said base 1 is provided with two side pieces 5 projecting from its upper surface and in each end of the said pieces 5 is revolvably mounted a shaft 6 having an aperture 7 therethrough and two parallel bars 8

projecting therefrom. Extending across the upper ends of the parallel bars 8 is a horizontal bar 9 from each of which latter is hung a figure 10 adapted to swing and revolve on said horizontal bars 9. Each of 50 the said shafts 6 is provided with a pin 11 adapted to pass through aperture 6 and into the aperture 12 in the base 1 when the parallel bars 8 are in the upright position.

When the toy is to be shipped the pin 11 55 is withdrawn from the aperture 12 in the base 1 so that the parallel bars 8 can be folded down with the figure 10 resting upon the base 1 between the sides 5 to prevent breakage of the said parallel bars or figures, 60 in shipment.

Having thus described my invention, what I claim is:—

1. A toy comprising a base having an aperture in each end, wheels upon which 65 said base is mounted, said wheels being mounted off their centers, sides projecting above said base, a shaft revolvably mounted in said sides at each end of said base and having an aperture therethrough, a pin 70 adapted to pass through the aperture in each of said shafts and into the aperture in the base, parallel bars projecting from each of said shafts, and a figure revolvably hung from each of said parallel bars. 75

2. A toy comprising a base having an aperture in each end, wheels upon which said base is mounted, sides projecting above said base, a shaft revolvably mounted in said sides at each end of said base and having an 80 aperture therethrough, a pin adapted to pass through the aperture in each of said shafts and into the aperture in the base, parallel bars projecting from each of said shafts and adapted to be folded down between said sides 85 when said pin is removed, and a figure revolvably hung from each of said parallel bars.

In testimony whereof I affix my signature.

FRANK L. DORSK.
